UNITED STATES PATENT OFFICE

2,382,077

POWER PRESS BRAKE AND DIE SET

Freeland H. Leslie, Chicago, Ill.

Application August 3, 1942, Serial No. 453,306

19 Claims.

(Cl. 164—86)

This invention relates to power press brakes and die sets, sometimes called sub-presses. It embodies self-balancing concepts disclosed in applicant's United States Letters Patent No. 2,260,183 and in applicant's copending application Serial No. 394,971 which is a continuation in part of said patent.

The general object of this invention is to provide a sub-press which will make it possible to perform punching operations on press brakes no matter how old, worn out and sprung the press brake may be so long as it will move its ram up and down.

Applicant attains this object by holding the punch holder and the die shoe in alignment by means independent of a given relationship between the ram of a press and its bed and by then moving the punch holder toward the die shoe by means of the ram, there being no rigid connection between the ram and the punch holder. Contrasting this with present practice, generally speaking, the punch holder which holds the punches is rigidly fastened to the bottom of the press ram while the dies are rigidly fastened to the bed of the press. This relationship of the punch holder to the ram and of the die shoe to the bed is true in straight side presses as well as in press brakes. It is apparent, therefore, that alignment of the punches and the dies requires alignment of the ram and the bed, and conversely, when the ram becomes misaligned, the punches cease to register exactly with the dies.

In order to resist the misalignment of the ram, which is held in a vertical path by means of slides and ways, it has been common practice to maintain alignment between the punch holder and die shoe by means of leader pins and bushings. Thus, in a rectangular leader pin die set, there may be projecting upwardly from the die shoe a pair of leader pins at each end thereof which register with bushings in the punch holder. When this die set is positioned in a press, the die shoe is rigidly fastened to the bed and the punch holder is rigidly fastened to the ram with the result that the leader pins acting on the bushings tend to align the ram with the bed of the press and to assist the ways and slides guiding the ram.

In the present invention, applicant departs from the practice of fastening the punch holder to the ram but relies solely upon the die set for holding the punches and dies in alignment and permits the ram of the press to strike the upper part of the die set in a very inexact way. The die set bears the burden of holding the punches

and dies in alignment without assistance from the ram.

More specifically, the object of this invention is to provide a superior die set for use in press brakes and, as will be seen, the advantages mentioned above resulting from the employment of a non rigid connection between the ram and the die set are particularly important in press brake applications.

A press brake is a tool for making bends in metal sheets. Essentially it consists of two upright end members held in spaced relationship by a bottom member and a top member with a ram having a length approximately equal to the width of the press brake and a depth of two or three inches, said ram depending from the upper part of the frame and capable of vertical movement in response to the application of power. Disposed below the ram is a bed of similar width and similar depth. For bending operations, a die, as for example a V-shaped die will be mounted on the bed and a V-shaped punch for seating itself in the die will be mounted on the bottom of the ram. By placing a piece of work on the die and causing the ram to descend, the two ends of the piece of the work will bend upwardly to place the requisite bend in the piece of work. These press brakes may have a width as high as 20 feet and the tolerances of the guiding means for the ram are so great that it is not good practice to attempt punching operations with a press brake. Indeed the successful functioning of press brakes in bending operations depends to no small extent upon the fact that the dies are able to align themselves and upon the fact that it is possible to employ punches which have aligning portions for engagement with complementary portions in the dies.

At the present time when it is desired to perform punching operations on a press brake there is positioned therein a somewhat conventional leader pin die set consisting of a punch holder and a die shoe with leader pins positioned at either end of the die set directly under the ram, there usually being only two leader pins. As indicated before with respect to all types of presses, the leader pin die set when used in a press brake has its die shoe rigidly fastened to the press brake bed and its punch holder rigidly fastened to the ram. A press brake, however, must surmount an additional problem. In the case of the straight side punch press, the area of the bed of the press and the bottom of the ram determine approximately the maximum area of the punch holder and die shoe of the die set.

In the press brake, on the other hand, the bottom of the ram may be only an inch or two deep and the same is true of the bed. The die set that it is desired to mount therebetween, may be as wide as the press brake and one or two feet deep. It is necessary, therefore, to provide lateral support for the punch holder and the die shoe both in front of and behind the ram and the bed respectively. This lateral support is provided by an upper bolster plate and a lower bolster plate. These press brake bolster plates consist of heavy pieces of metal, approximately coextensive with the width of the press brake between the two vertical frame members and having a depth, or a portion extending in front of the ram and behind the ram, of perhaps as much as a foot. In the case of the upper bolster plate, which is mounted centrally of the ram, there are angle supports extending upwardly to engage the front and the back of the ram. The lower bolster plate is the same as the upper bolster plate but is turned upside down. In the case of a 20 foot press brake, the two bolster plates may weigh several tons.

One major object of this invention is to impose the entire burden of resisting forward and backward rocking of the punch holder and die shoe upon the punch holder and the die shoe or upon the die set. Certain important advantages or results follow from the attainment of this object and these will be discussed after this object has been clarified. A press brake will be used as an illustration. If a die set consisting of a punch holder and die shoe with leader pins and bushings were simply positioned between the shallow ram and the shallow bed of a press brake there would be some difficulty in establishing the conventional rigid connections between the ram and the punch holder on the one hand and the die shoe and the bed on the other. Additionally if the die set were loaded forwardly or rearwardly off center, conflicting forces would be set up in the ram which would tend to put uneven strain on the slides and ways guiding the ram. For this reason, there is placed between the bottom of the die shoe and the bed a heavy bolster plate which extends approximately as far forwardly and as far rearwardly of the bed as does the die shoe. A similar bolster plate inverted is positioned between the top of the punch holder and the bottom of the ram. These bolsters have inwardly directed arms to engage the front and the back walls of the ram and bed to prevent forward and backward rocking between the punch holder and ram and between the die shoe and the bed when the die set is loaded forwardly or rearwardly off center. The surfaces of the bolster plates which engage the punch holder and the die shoe are, of course, horizontal and these bolster plates are very heavy. They are intended to take up certain distortional forces and consequently the weight or strength of the punch holder and die shoe is not so important a factor. In the case of applicant's present invention, however, the punch holder and the die shoe or whatever part of the die set which is actually holding these two members must be capable of withstanding all of these distorting forces because there is no rigid connection between the ram and the die set.

By providing punch holders and die shoes, or more broadly by providing a die set having the strength to take up all forward and backward rocking of the punch holder and die shoe with respect to each other due to off-center loading of

the die set, applicant attains two important advantages which are particularly striking in the case of the press brake. In the first place applicant eliminates the need for the bolster plates. 5 By eliminating the bolster plates, applicant has removed a die set erection problem of considerable proportions. In order to convert a press brake which was being used for bending operations to a device useful for punching and blanking, it has always been necessary to mount these bolster plates on the ram and the bed, and in the case of a 20 foot press brake these bolster plates weigh several tons. In order to mount the bolster plates, special hoists and other equipment is necessary. Applicant's construction, employing a sub-press similar to that shown in applicant's Patent No. 2,260,183 and in the copending application Serial No. 394,971, renders the bolster plates unnecessary. The second advantage arises from the fact that applicant may use whatever weight punch holder and die shoe is necessary to handle the particular number of punches actually to be used in a given operation whereas at the present time the weight of 10 the punch holder and the weight of the die shoe is controlled primarily by the bulk and the size of the press brake. Thus under present practice, one may see a 20 foot press brake raising and lowering enormous bolster plates and the punch holder of an enormous die set when upon inspection it is found there may be a dozen or so small blanking dies distributed over the 20 foot length of the sub-press which blanking dies require only a few tons of pressure to drive through, 15 for example an aluminum airplane wing section. The actual punching capacity could be handled by an ordinary punch press having a bed six inches by six inches. By applicant's construction, on the other hand, a comparatively light 20 punch holder and die shoe can be used as component parts of the die set or sub-press and the press brake will function with very little load on it.

Another object of this invention is to make a 25 die set wherein punches and dies may be readily changed while the die set is in the press brake. Mention has been made before of the great weight of conventional die sets and bolster plates and of the fact that the bolster plates completely cover 30 the top of the punch holder and the bottom of the die shoe and make it impossible, under conventional punch mounting, to remove a punch or a die without taking the die set out of the press brake. By applicant's invention, wherein 35 the ram is in non-rigid engagement with the upper part of the die set, no tortional forces are transmitted to the ram since it performs no aligning function whatever for the punches and dies. The same is true of the relationship between the die shoe and the bed with the result 40 that applicant eliminates both the upper and lower bolster plates. This requires considerable explaining. Treating of the die shoe, a die is mounted on a die shoe by means of dowels, which 45 are here unimportant, and headed screws with the heads on the outer side of the die shoe. These heads fit into counter bores so that the bottom of the die shoe will be flat so as to permit it to 50 rest upon the flat top of a bolster. When a die becomes dull, the surface of the die is ground to make it sharp and if the screw heads were adjacent the surface of the die, it would be necessary to lower the counter bore. For this reason 55 general practice has the screw heads on the side 60

70

75

away from the cutting edges of the dies. This same practice is followed in the case of mounting the punch plate on the punch holder. It is immediately apparent that a punch plate cannot be removed from a punch holder of the die from the die shoe without taking the die set out of the press. The result is that in conventional practice it is common to lift heavy die sets out of a punch press merely for the purpose of sharpening one or two dies or for replacing one or two punches.

At this point, definitions are given of some of the terminology used, herewith, in connection with dies. In a conventional leader pin die set, the punch holder is the upper part of the die set and supports the punches while the die shoe is the lower part of the die set and supports the dies. In the applicant's die set herein described, the same holds true. Punches may be attached directly to the punch holder or through auxiliary members known as punch plates, retainers or pads. Dies may be attached directly to the die shoe or through auxiliary pieces called die plates, retainers or pads.

By applicant's invention, the punch holder and the die shoe receive all torsional strains and they move toward each other solely by the action of the narrow contact of the bed of the press with the bottom of the die shoe and the almost fine contact of the bottom of the ram with the top of the punch holder. This leaves the top of the punch holder and the bottom of the die shoe exposed with the exception of that comparatively narrow strip one or two inches wide immediately above the bed of the press or below the ram. It is unnecessary to counterbore for the screw heads that hold the punch plate to the punch holder or for the screws that hold the die to the die shoe. One of the features of applicant's invention is the use of hexagonal cap screws which protrude above the punch holder or below the die shoe. To remove either the punch plate or the die, all that is necessary is to loosen and remove the screws and dowels that hold them. The die set does not have to be removed from the press brake in order to do this because all of the screw heads can be reached with a wrench and there is a plenty of room to knock out dowels with a drift and a hammer without removal of die set from press brake.

A feature of applicant's invention is the provision of holes through the punch holder and the die shoe at selected points to permit the mounting of punch plates and dies while the die set remains in the press brake. Punches and dies may be fitted to the punch holder and die shoe by means of locating holes while the die set is on the bench so at any later time the same locating holes may be used to align punches and dies even when the die set is in the press brake.

Another object of this invention is to permit full utilization of the throat of a press brake when punching operations are to be performed. When leader pin die sets are used on press brakes, the leader pins are located on the center line of the ram and bed. In order to use a 10-foot press brake in punching along the edges of a 30-foot sheet, it may be necessary to utilize the throat depth of the press brake because the length of the sheet greatly exceeds the width of the press brake. Applicant's balanced die set relying upon backwardly extending arms for providing alignment of the punches and dies does not nullify the throat depth of the press as do the leader pins.

A further object of this invention is to use the top part of the upstroke of the ram to raise the punches out of the dies so as to permit removal or positioning of the work. As made clear in the copending patent application and in the patent, applicant mounts the pivot point in approximate alignment with the top of the dies and in common practice the two leaves are positioned substantially parallel, with the punches just touching the tops of the dies. The weight of the punch holder and the punch plate will cause the punches to rest inside the dies. This being normal position, it is necessary to provide a means for raising the punch plate and the punches sufficiently far to permit the insertion or withdrawal of the work.

Another object of this invention is to provide a new and improved die set or sub-press. A major improvement of applicant's sub-press lies in the provision of a somewhat curved surface for controlling the bending of the flexible steel member and for shifting the flexing point. Applicant's die sets are positioned between the narrow ram and bed of a press brake and if the punch loading is unbalanced or off center, that is if a greater amount of punching is being done in front of the ram than is being done behind the ram and conversely, bending strains are communicated by the upper and lower members of the die set to the spring steel pivot plate causing bending of the spring steel pivot plate. This bending is a separate action from the bending of the spring steel pivot plate when it acts as a hinge or pivot to restrict the motion of the punches in moving toward and away from their respective dies. Applicant provides stops which act on the spring plate so as to prevent this action, or at least limit it, regardless of the direction of the off center loading.

Another object of this invention is to provide a broad sub-press employing a plurality of pivot points, which are in alignment but are not co-extensive with the width of the sub-press.

Another object of this invention is to provide end stops to control the degree to which the punch plate holder may drop toward the die shoe. As the weight of the punch plate holder is increased, it will increase the inclination of the punches to enter the dies when not controlled by some lifting force. In applicant's type of sub-press in which the punch approaches the die along an arc, it is apparent that the farther the punch enters the die, the greater the strain of the punch will be upon the die wall. As nothing is accomplished by having the punch enter the die by more than a small fraction of an inch, applicant has positioned end stops on the sub-press which sustain the punch holder at a predetermined minimum level. The top members of these stops can be raised with the punch holder to permit the passage of work between the top and bottom members of these stops.

Another object of this invention is to suspend the die set from the frame of the press brake and support its front edge on the bed. In conjunction with this, applicant has provided a simplified method of making the sub-press.

These and such other objects as may herein appear are obtained in the embodiment of the invention disclosed in the accompanying drawings wherein:

Figure 1 is a perspective view of a press brake with applicant's sub-press mounted therein;

Figure 2 is a view taken on the line 2—2 of Figure 1 and showing the sub-press with the punches immediately above the dies;

Figure 3 is a view, partly cut away similar to Figure 2 showing applicant's sub-press in the open position;

Figure 4 is a view taken on the line 4—4 of Figure 2;

Figure 5 is an enlargement of the forward part of the upper leaf of applicant's sub-press and the lower portion of the ram for the purpose of illustrating the nature of the contact between the bottom of the ram and the top of said leaf;

Figure 6 is a diagrammatic illustration showing the position of the flexing leaf with respect to limiting stops when the die set is loaded off-center forwardly at the moment when the punches enter the work;

Figure 7 is a diagrammatic illustration similar to Figure 6 where the die set is loaded off-center rearwardly;

Figure 8 is a diagrammatic view illustrating the position of the flexing leaf when applicant's die set is in the open position; and

Figure 9 is a fragmentary plan view of the top of applicant's punch plate illustrating uniform positioning of holes for mounting punch holders thereon.

Applicant's die set used with a reciprocatable ram

Referring to Figure 1 of the drawings, the numeral 10 generally identifies a press brake. The press brake is of a conventional type and consists of two upright end supporting walls 12 and 14 held in upright relationship by a lower connecting member 16 and upper connecting member 18. The throat of the press brake may be seen in Figure 2 and bears the numeral 20. Returning to Figure 1, ordinarily in press brakes, if the work piece is narrower than the distance between the two end walls 12 and 14, the work may be advanced straight through the press, that is withdrawn from the back. The depth of the throat, that is the distance from the vertical plane containing the ram, shortly to be described, back to the rear of a gap in the end walls varies according to the capacity of the press. Generally speaking in press brakes, the depth is not very great.

Mounted in the forward lower portion of the press brake 10 is a bed 22 which may be removable or fixed and of various shapes. Generally speaking the bed is coextensive or slightly exceeds the distance between the wall members 12 and 14 of the press brake and generally speaking has a depth, that is from the point 24 to the point 26, of one to three inches. Disposed above the bed and in general vertical alignment therewith is a ram 28 which may be reciprocated vertically by means 32 and 34, which means may assume a variety of types and need not here be discussed.

Suffice it to say, for applicant's purpose, the press brake must have a bed and a ram reciprocable with respect to the bed. The presence or absence of great accuracy in the vertical movements of the ram 28 is not important.

Applicant's sub-press is generally identified by the numeral 30 and consists generally speaking of a die shoe 32 mounted on the ends of a plurality of inverted channels, or lower leaf members, 34 and 36 which in turn are connected through a plurality of flexible leaves such as 38 and similar upright channel members 40, 42

and 44 to a punch holder 46. The flexible leaves 38 are all in alignment with each other and it will be understood that this employment of a plurality of upper leaves and a like plurality of complementary lower leaves connected by a plurality of flexible leaves is an adaptation of applicant's invention in United States Letters Patent No. 2,260,183 to a situation where a very broad punch plate is to be used. The parts actually making up the die set can be better seen in Figure 2 where it will be noted that the flexible leaf 38 is rigidly fastened at its outer end to the upper channel member 40 through the medium of an elongated pressure block 48 while it is rigidly attached to the lower channel member 34 through the medium of a block 50. The lower limiting member 52 and the upper limiting member 54 clearly shown in Figure 2 are auxiliary features which will be discussed later.

The means for assembling applicant's sub-press with the press brake is quite simple. Rigidly fastened to the bottom of the die shoe 32 along its median line is a T shaped member 56 having a depending tongue 58 adapted to fit between two heavy plates 60 and 62, continuing to refer to Figure 2, which in this particular press brake together make up the bed 22. It is of course understood that the bed of a press brake may consist of a single plate having a groove therein to receive the tongue 58. The ends of set screws (see 61 in Figure 2) in the bed 22 are screwed against the tongue 58 to clamp the T shaped member 56 rigidly to the bed 22. It is important at this point to bear in mind that the bed of the press brake, while it may be removable or adjustable up and down, is in operation a fixed element, that is to say it bears a rigid relationship to the two end walls 12 and 14 and the connecting members 16 and 18 of the press brake.

The rear of the sub-press 30 is suspended from a pair of brackets attached to the inside of the end walls, one of which brackets carries the numeral 64 and another is suggested in dotted outline and carries the numeral 66. Extending across the rear of the press brake and connecting the two brackets 64 and 66 to each other is a heavy channel member 68. This heavy channel member 68, referring now to Figure 4, is connected to the blocks such as 50, which extend on both sides of the lower channel member 34 by bolts 70 and 72 passed through spacer members 74 and 76. These connections are all tight.

Referring now to Figure 2 therefor we may view the lower leaf or lower portion of applicant's sub-press when mounted in the press brake as a part of a rigid bed extending from the bracket 64 to the bed 22. Whatever movement is to be permitted between the upper and lower parts of applicant's sub-press will, with respect to the press brake as a whole, occur commencing with and between the flexible leaf 38 and the punch holder 46.

Referring to Figure 2, attention is directed to a lower end block 78 which, as may be seen in Figure 1, is disposed at the end of the die shoe. The top surface 80 of this block lies in a plane parallel to the plane of the top of the die shoe 32 which plane is the deepest level, as 82, see Figure 2, in each die to which it is desired to permit the punch to penetrate. It will be understood from reading United States Letters Patent No. 2,260,183 that punches mounted in applicant's sub-press are moving along an arc. The walls of the die and the walls of the punch are approxi-

mately tangent to the arc at the surface of the die, that is the point where the punch enters the die, and it follows that the punch must not be permitted to penetrate the die very far because it will wear its walls against the die walls. The lower end block 78 functions with a similar block 84, see Figure 1, in conjunction with the upper end blocks 86 and 88 to prevent the punches from penetrating the dies to an undesirable point. In Figure 1, the sub-press is shown fully closed, that is with the end blocks 86 and 88 resting on the end blocks 78 and 84 respectively so that the punches have attained their maximum depth in the dies. In Figure 2 the bottoms of the punches are shown just above the tops of the dies so that there is a space between the end blocks 78 and 86. This position never exists as a matter of practice. It is shown for the purpose of illustrating the plane containing the top surfaces of the dies which is at right angles to the side walls of the punches. This plane also contains the flexible leaf 38. When the punches are drawn above or depressed below that plane, they are moving along an arc having as its center some point in the flexible leaf 38.

In Figure 3 the uppermost position of the upper leaf 40 of applicant's sub-press is shown. Mounted centrally of the length of the top of the punch holder 46 is a strip 48, which therefore lies directly below the ram 28. The lower edge of the ram is cut out to receive a bar having an inverted L cross section 90. The bar 90 is held by a second bar 92, having a groove 94 therein, by bolts such as 96. Referring for the moment to Figure 1, bolts 98 and 100, performing the functions of bolt 96 also hold a bracket 102 to the forward lower edge of the ram 28. Similarly bolts 104 and 106 hold a bracket 108 to the lower edge of the ram 28 near its other end. Referring both to Figure 1 and Figure 2, two double brackets 110 and 112 are mounted on the outer top surface of the punch holder 46 and pivotally supported in each are lift rods 114 and 116 on the upper end of which are stop members 118 and 120, the position of which on the lift rods 114 and 116 may be adjusted by the threaded connection thereon, and the position fixed by lock nuts 122 and 124. Referring to Figure 3 the top member 118 is positioned at a height such that the punch holder 46 will be lifted by the rising ram for perhaps half an inch during the last part of the upstroke. The stroke of the ram may be several inches, but all of this stroke is not used in applicant's sub-presses. The bar 90 may be called a striking bar and its striking edge may be oiled. Ordinarily the punches are raised above the dies by a distance just sufficient to permit the ready insertion or withdrawal of the work.

It will be noted that the construction shown does not include a stripper. As is well understood in the art, when the punches pass through the work piece into the dies, and then move back upwardly, they will carry the work piece upwardly unless some means is provided for stripping the work piece from the punches. It was not thought wise to include a stripper in the present embodiment.

The structure thus far described has certain advantages when employed in a reciprocating ram press. In the first place, referring to Figure 2, the die shoe 32 and the punch plate 46 have sufficient strength from front to back in conjunction with channel bar members 34 and 40 securely fastened thereto, to resist distortion

caused by the forces used for punching. Consequently the punch holder 46 and the die shoe 32 can be of whatever size is necessary to accommodate the total length and width of the cutting surfaces of the punches to be employed, the thickness and hardness of the work piece also being taken into consideration. If the work piece is light and the punches are few, the weight of the die shoe 32 and punch holder 46 as well as the other members of the sub-press may be correspondingly lightened. This will facilitate handling.

An appreciation of the value of applicant's sub-press may perhaps be more quickly conveyed by using the term "self-balancing." The forces that damage punch presses and dies are forces which cause the punches to move horizontally out of alignment with the dies. Where the punch holding means and the die shoe are rigidly fastened to the ram of a press brake or a press and to the bed, the distorting forces are transmitted to the ram and to the bed. This is true of leader pin die sets in which the punch holding means is rigidly fastened to the ram and the die holding means is rigidly fastened to the bed of the press brake or punch press. In applicant's self-balancing die set, all of these forces are exhausted within the sub-press itself and are not transmitted in any way to the press brake or the punch press. There are no horizontal forces affecting the ram or the bed. Consequently a perfect balance is obtained with vertical forces only, regardless of where the punches are located on the punch plate. No horizontal strains can be transmitted to the ram or bed.

Moreover, for purposes of illustration, the dotted lines 126, 128, 130 and 132 indicate the shape, as viewed from the side in Figure 2, of the heavy bolster plates that are ordinarily hung from the bottom of a ram and placed above the top of a bed for assisting in holding the punch holder rigidly on the ram and the die shoe rigidly on the bed. Applicant has completely dispensed with these bolster plates because no attempt is made to relate the up and down movement of the ram to the alignment problem of the sub-press. Referring to Figure 5, it will be noted that the bottom of the striking bar 90 engages the strip 48. It is immaterial whether the striking bar 90 engages the strip 48 between the points 134 and 136 or between the points 136 and 138. The net result of this is that it does not make any difference whether the means for guiding the ram 28 in its vertical movements is worn so much that the ram 28 may also move sidewise between the points 140 and 142 or whether its guiding means is so accurate that the ram 28 moves vertically within a tolerance of one-ten-thousandth of an inch in its sidewise motion. So far as moving the upper leaf 40 carrying the punch holder 46 of applicant's sub-press is concerned, the alignment between the punches and the dies will be just as good when the sub-press is in a much used press brake in which the ram has a forward and backward play of one-sixteenth of an inch as when applicant's sub-press is mounted on a new press brake having a tolerance of one-ten-thousandth of an inch if such a press brake can be made.

The structure described and drawn shows a means for performing punching operations on press brakes no matter how old, worn-out and sprung the press brake may be so long as it will move its ram up and down.

Punch and dies removable from die set while latter is mounted in the press

Applicant's punch holder 46 and die shoe 32 are designed to permit the removal of punches and dies without taking the entire sub-press out of the press brake.

Referring to Figure 1 there is shown a plurality of die retainers, dies, punch retainers and punches of which the central group will be discussed. The numeral 144 identifies a die, 146 a punch and 147 a punch retainer, plate or pad. Sometimes there is a die plate between the die 144 and the die shoe 32, see for example 146. The die 144 is held to the die shoe 32 by a plurality of screws, as for example 148 and 150. In order to prevent horizontal movement of the die 144 with respect to the die shoe 32, dowels are employed in the customary manner and these are not shown. The screws 148 and 150 may be located any place on the shoe 32 excepting in alignment with the die and excepting in alignment with the T-shaped member 56 which rests upon the bed 22 of the press brake. As mentioned heretofore, in present day practice, where the die shoe of a conventional leader pin die set rests upon a bolster which has a flat area and has its sides extending from both front and back of the press brake bed, see the dotted lines 130 and 132 in Figure 2, it is necessary that the heads of screws 148 and 150 be in counterbores on the under surface of the die shoe 32, and it follows that it is impossible to get at these screw heads when the sub-press is mounted on the bolster plates of the press brake.

By applicant's construction, however, the bolts 148 and 150 are cap screws of any suitable type and not counterbored for at all. A die such as 144 is held by a plurality of screws such as 148 and 150 disposed in front of and in back of the bed of the press brake and if this particular die becomes worn, all that is necessary is to loosen the bolts such as 148 and 150 and remove the dowels by a drift in the conventional manner. Similarly, the associated punch retainer 147 is suspended from the punch holder 46 by screws with heads positioned above the top of the punch holder 46. The punch plate may likewise be removed.

This is an important feature of applicant's construction. Dies and punches do not wear out at the same rate. Consequently, after a sub-press having a large number of punches and dies mounted therein has been used for a while in a press, one or two of the punches may become dull while all the rest continue to be usable. It is possible to sharpen these few punches or dies without the necessity of removing the entire sub-press from the press brake, an operation which may require much expense and delay.

In connection with the removability of dies, applicant provides a punch holder such as 46 and a die shoe such as 32 having dowel holes and screw holes very exactly positioned according to a given pattern. Referring to Figure 9, the larger holes such as 152 and 154 indicate screw holes while the smaller holes such as 156 and 158 indicate dowel holes. These holes may be extended along the entire top of the punch holder and die shoe respectively. The punch retainers may be standard size rectangular blocks such as 160 and 162, the sizes being such that a plurality of them may be caused to exactly fill in the entire bottom of the punch holder 46. By this arrangement, it is possible to mount

punches and dies on punch plates and die plates on a bench and then locate the punch plates and die plates at any desired positions in the sub-press while the sub-press is mounted in the press brake. A template may be provided on the work bench for showing the exact position of the holes on the punch holder and the die shoe respectively. By simply using the template on the punch plates and the die plates while on the work bench it will be possible to locate the punches and dies so exact registry is obtained when they are mounted in the sub-press while the latter is in the press brake.

While this phase of applicant's invention is particularly applicable to the press brake when the press brake is used for punching operations because of the narrowness or shallow depth of the press brake ram and bed, and while it is not so applicable to the ordinary straight side press because the bottom of the ram is usually of a width and depth sufficient to define the area in which punches are to be mounted, it is anticipated that in the use of applicant's sub-presses on straight side punch presses the bottom of the ram may be altered to assume a somewhat line configuration similar to the ram of a press brake and under such circumstances the employment of applicant's type of punch holder having most of its upper surface exposed will be possible. The 30 bolster plate of straight side punch presses may be similarly modified.

New and improved pivot point

When one of applicant's sub-presses such as 35 that shown in Figure 1 is loaded with punches in such a way that it is exactly balanced, that is the punches at the left end equal the number at the right end and the distance from the front, back and sides for the respective punches is the 40 same, the sub-press may be said to be loaded on center. Such loading, however, is rarely possible. The places where holes are to be made vary and the result is that the distribution of the cutting surfaces of the punches over the punch plate is 45 not even or equal. On the contrary there may be excess loading at one end or the other or there may be excess loading forwardly or backwardly.

So far as excess loading to one side or other 50 of applicant's sub-press is concerned, no serious problems arise because not only are the punch holder and die shoe made of sufficiently heavy material but they are supported along their length by the very heavy bed or ram of the press brake.

55 In the case of off-center loading forwardly of the ram or behind the ram, however, certain distortional forces are transmitted to the flexible leaf 38. The two types of distortional forces are diagrammatically illustrated in Figures 6 and 7. 60 In Figures 6 and 7 the arrow 164 indicates the direction and position of the downward force exerted by the ram on the punch holder 46 while the arrow 166 indicates the direction and position of the resisting force by the press brake bed on the die shoe. The oppositely disposed arrows 168 and 170 represent the opposed forces 65 acting on the punch holder 46 and die shoe 32 respectively when a punch and die are positioned at the arrows and the punch is forced 70 against the work piece. There being no other punches and dies mounted to the right of the ram force 164, the force 168 attempts to use the ram indicated by the arrow 164 as a fulcrum forcing the rigid upper leaf comprising the 75 punch holder 46, the channel bar 40 and block

48 as a lever to put a slight kink 172 in the leaf 38. In other words, while the leaf 38 has sufficient structural strength to act as a column when misaligning force is applied along an arrow such as 174, when the misaligning force is applied along such as indicated by the force 176 the leaf will yield. In yielding, it may draw the upper leaf assembly including the channel member 40 and punch holder 46 slightly to the right, which would get the punches and dies out of alignment.

In order to defeat this effect, and bearing in mind not only that the leaf 38 is lying in approximately the same plane as the top of the dies and that the punches are permitted to enter the dies by only a short distance such as one-eighth of an inch, applicant has positioned a stop block 178 beneath the free end of the leaf 38 to act as a stop preventing the free end of the leaf 38 from being depressed below the level necessary to permit the punches to enter the dies approximately one-eighth of an inch.

Beneath the flexible leaf 38 is a lower limiting member 52, the function of which will shortly be described, but which occupies a portion of the space between the flexible leaf 38 and the block 178, a space which could be occupied by the block 178 if the lower limiting member 52 were not employed. Under normal operating conditions where the sub-press is loaded on center or substantially on center, the lower limiting member 52, attached to the flexible leaf 38, will only touch the block 178 when the punches have penetrated the dies to their maximum extent. When, however, there is substantial forward off-center loading and the effect of the force 168 operating across the ram force 164 as a fulcrum, is to depress the block 48 abnormally so that it would twist and damage the flexible leaf 38, this action is permitted only until the leaf and lower limiting member 52 engages the block 178, at which time, the block 178 becomes the fulcrum and the ram force 164 overcomes the force 168 and forces the punch through the work piece into the die. No substantial damage is caused to the flexible leaf 38.

When, on the other hand, referring now to Figure 7, the off-center loading is rearwardly, that is behind the ram, the punch entering the work sets up a force 180 which tends to utilize the ram force 164 as a fulcrum and move the inner end including the block 48 upwardly. The effect of this action, if the leaf 38 had no support to the left of the dotted line 182, would be to so seriously strain the flexible leaf 38 at the point 184 as to break it quickly.

To overcome this difficulty applicant uses the upper limiting member 54 and the lower limiting member 52 which have curving surfaces 184 and 186. As the force 180 is applied, the flexible leaf 38 follows the curve 184, the actual flexing point moving to the left from the point 182. The distance between the curved edges 184 and 186 less the thickness of the flexible leaf 38 is slightly greater than the opening 188 beneath the lower limiting member 52 and the block 178, referring to Figure 2 when the press is in normal condition. The result is that the lower limiting member 52 engages one side of the flexible leaf 38 while the upper limiting member 54 engages the opposite side of the leaf 38 after the distortional force 180, see Figure 7, has been permitted to function for a short time.

It will be understood that it is necessary to permit a slightly greater upward movement of

the leaf 38 than downward movement because the leaf must be raised by the press brake to permit the insertion and removal of work. This is illustrated in Figure 8 where the leaf is raised to its maximum position. It is noted that under such circumstances the curved surface 186 of the lower limiting member 52 does not engage the leaf 38 at all. The curvatures of limiting members 52 and 54, that limit the degree of flexing of leaf 38, are such that it is not possible for leaf 38 to be bent so severely at any point that its metal is strained beyond the practical working strain for springs.

Method of making applicant's sub-press

One of the features of applicant's invention resides in the method of joining the various parts of the press to each other, which in turn makes it possible to use ordinary hot rolled plates, angle irons and channel irons to make applicant's invention in conjunction with a planer. Referring to Figure 2, the die shoe 32 may be made from a hot rolled plate by means of a planer. It is, of course, absolutely essential that the top of the lower block 50 be in a plane absolutely parallel to the top of the die shoe 32. After the block 50 and channel member 34 have been welded together as shown by welds 194, Figure 4, the welded assembly is planed on surface 190 and on the top of block 50 in one setting thereby insuring that these surfaces are parallel. Channel irons 34 and 40 may be assembled with the die shoe 32, and punch holder 46 respectively by means of screws and dowels, see Figure 2. The top surface of the lower block 50, continuing to refer to Figure 4, will be parallel to the plane of the top of the die shoe and may be used as a base for obtaining a support at the rear of the punch press which will result in the sub-press occupying a normal horizontal position.

The foregoing is a disclosure of the general idea of several features of applicant's invention. It will be understood that fundamentally the lack of a non-rigid connection between the ram and the top of the punch plate eliminates the necessity of maintaining exact alignment of the ram during its reciprocating vertical movement. By separating the punch plate from the ram, moreover, the employment of bolster plates has been eliminated with the result that top of applicant's punch plate is exposed and protruding screw heads may be used for holding punch plates to the punch holder with the fortunate result that punch plates may be removed from applicant's sub-press while the sub-press remains mounted in the press brake. Certain improvements in stops for protecting the flexible leaf have been disclosed as well as a sub-press which may be made from hot rolled plates and channel or angle stock with great accuracy with the type of tools that almost every machine shop possesses.

A great advantage of the sub-press disclosed here for the first time by applicant lies in the fact, referring to Figure 2, that the die shoe 32 and the lower channel member 34 are identical in weight and strength with the punch holder 46 and upper channel member 40. This construction differs from that disclosed in applicant's issued Patent No. 2,260,183 and in applicant's pending application Serial No. 394,971 in that in those structures the lower arm or leaf of applicant's sub-press was much heavier and consequently proportionately more inflexible than the upper member. In the present construction they are equally inflexible with the result that, re-

ferring to Figure 6, where the off-center loading forwardly of the ram force 164 is very great so as to slightly bow the upper channel member 40, a like reverse bowing will occur in the lower channel member 34 with the result that the bottom of a punch depending from the punch holder 46 will be moved outwardly of its original position to exactly the same extent as will the top of its associated die member mounted on the die shoe 32. This result would not obtain where the upper channel member 40 is substantially lighter than the lower channel member 34. Under such circumstances, the upper channel member 40 would bow much more than the lower channel member 34. The curved lines 196 and 198 in Figure 6 exaggerate the degree of curvature of the channel members 40 and 34 that may occur. In Figure 7 the curved lines 200 and 202 similarly exaggerate the inward bowing that may result where the load represented by the force 180 is disposed behind the ram represented by the force 164.

One of the major advantages of applicant's sub-press over the conventional leader pin die set as used in press brakes arises from its aligning means which does not incorporate leader pins or bushings. The capacity of a leader pin and bushing to hold a punch holder and die shoe in alignment in the case of off-center loading of the punches is additionally conditioned upon the accuracy of the alignment of the ram to which the punch holder in the conventional leader pin die set is affixed. When the slides and ways which guide the ram in its vertical course permit a great deal of play, the aligning load is transmitted to the leader pins. When these leader pins are not constantly oiled and even when oiled, when the ram is greatly out of alignment, the leader pin will jam in the bushings, will force the bushings out of the punch holder and in some cases will destroy the punch holder. This action of the leader pins is primarily responsible through the little use currently of leader pin die sets in press brakes. It will be understood that applicant is at present employing conventional means for removing slugs from the dies. In Figure 2 dotted lines through the die shoe from the two forward dies indicate a vertical and a sloped discharge slot. In conventional practice there are other ways for removing such slugs.

Having thus described my invention what I desire to claim as new and useful is:

1. A machine of the character described comprising a frame, a bed for supporting a die shoe, means supported on the frame for holding a punch holder above the die shoe and movable along an arc toward the die shoe, a reciprocatable ram normally spaced above said punch holder and engageable therewith for causing said punch holder to approach and withdraw from said die shoe, and means responsive to the movement of the ram toward its normal position for moving the punch holder away from the die shoe for facilitating the insertion of a work piece.

2. A machine of the character described comprising a frame, a bed, a sub-press disposed on said bed, a ram spaced from said sub-press when the ram is in normal position, means for reciprocating said ram so as to cause it to strike and close the sub-press, and an elongated bar disposed between the ram and the sub-press for transmitting the ram force to the sub-press whereby the upper surface of the sub-press is exposed.

3. A machine of the class described comprising a frame, a bed, a punching zone above said bed, a tool carrying member having a free end disposed in the punching zone and having a positioning end mounted on the frame outside the punching zone, means for permitting the free end of the tool carrying member to move in the punching zone, a reciprocatable ram disposed above the tool carrying member, means for maintaining the tool carrying member in alignment with the bed in the punching zone irrespective of the reciprocatable ram, and a narrow bar having a length approximating one dimension of the tool carrying member and disposed between the ram and the tool carrying member for transmitting ram force to the tool carrying member, whereby the upper surface of the sub-press is exposed.
4. A machine of the class described comprising a frame, a bed, a punching zone above said bed, a tool holding member having a free end adapted for holding tools positioned in said punching zone, and its other end mounted on said frame outside the punching zone, means for permitting the free end of said tool holding member to rotate through a limited arc toward the bed about a substantially fixed axis, a reciprocatable ram normally spacedly positioned above the free end of said tool holding member, and a comparatively narrow striking bar substantially parallel to said axis positioned between the ram and the tool holding member.
5. A machine of the class described comprising a frame, a bed, a punching zone above said bed, a tool holding member having a free end adapted for holding tools positioned in said punching zone, and its other end mounted on said frame outside the punching zone, means for permitting the free end of said tool holding member to rotate through a limited arc toward the bed about a substantially fixed axis, a reciprocatable ram normally spacedly positioned above the free end of said tool holding member, and a comparatively narrow striking bar substantially parallel to said axis positioned between the ram and the tool holding member.
6. A machine of the class described comprising a frame, a bed, a punching zone above said bed, a tool holding member having a free end adapted for holding tools positioned in said punching zone, and its other end mounted on said frame outside the punching zone, means for permitting the free end of said tool holding member to rotate through a limited arc toward the bed about a substantially fixed axis, a reciprocatable ram normally spacedly positioned above the free end of said tool holding member, a comparatively narrow striking bar substantially parallel to said axis positioned between the ram and the tool holding member, and means connecting the tool holding member to the ram for raising the tool holding member as the ram approaches its normal position.
7. A punch press comprising a frame, a bed, a ram, a punch holder disposed beneath the ram and having portions projecting beyond opposite sides of the ram, the tops of said portions being exposed, and means accessible from the exposed top of said portions for removably holding punching tools to the punch holder, whereby the punch-

ing tools may be removed from the punch holder without removing the punch holder from beneath the ram.

8. A punch press comprising a frame, a bed, a ram, a punch holder disposed beneath the ram and having portions projecting beyond opposite sides of the ram, the tops of said portions being exposed, holes through said exposed portions of the punch holder and means disposed in said holes for holding punching tools to the punch holder, said means being removable from above the punch holder without removing the same from beneath the ram.

9. A punch press comprising a frame, a bed, a ram, a punch holder disposed beneath the ram and having portions projecting beyond opposite sides of the ram, the tops of said portions being exposed, regular spaced holes positioned accurately through said exposed portions of the punch holder, a punch plate having similarly spaced holes for exact registry with said first named holes, and cap screws and dowels positioned in said holes for holding the punch plate to the punch holder whereby a punch may be accurately positioned in the punch holder by accurately positioning it in a punch plate.

10. A sub-press comprising a pair of spaced tool holding members affixed to each other along one side, a flexible member disposed between said tool holding members near the point of said affixation, whereby the free side of said spaced members may be moved toward each other to define a punching zone, and means for limiting the flexing in said flexible member so as to hold the bending of the leaf at any one point below its elastic limit.

11. A sub-press comprising a pair of tool holding members disposed in spaced relationship, said spaced relationship being maintained by a flexible leaf member having one side attached to one tool holding member and the other side attached to the other tool holding member, and limiting means for positively limiting the amount of bending of the leaf to a predetermined safe point.

12. A sub-press comprising a pair of spaced tool holding members, said spaced relationship being maintained by a flexible leaf member having one side attached to one tool holding member and the other side attached to the other tool holding member, limiting means engageable with the opposite surfaces of the leaf for limiting the degree of bend per linear unit to a point below its elastic limit, and stop means for positively stopping bending of said leaf after a selected degree of bending has been attained.

13. A sub-press comprising a pair of spaced tool holding members, said spaced relationship being maintained by a flexible leaf member having one side attached to one tool holding member and the other side attached to the other tool holding member, and stop means for positively stopping bending of said leaf after a selected degree of bending has been attained.

14. A sub-press comprising a base tool holding member generally horizontally disposed, a block on the upper side thereof, a flexible leaf having one end mounted on said block and disposed in a substantially horizontal position, a second tool holding member having one end affixed to the free end of said flexible leaf so that the free end of the second tool holding member will be disposed adjacently to the free end of the first tool holding member, a limiting member mounted on top of the fixed end of the leaf and having a curved surface extending from contact with the

leaf upwardly and outwardly in the direction of the free end of the leaf, whereby the free end of the leaf if moved upwardly will contact the curved surface and eliminate excessive bending at any one point in the flexible leaf, and a second limiting member mounted beneath the free end of the leaf and having a curved surface extending from contact with the leaf downwardly and inwardly in the direction of the fixed end of the leaf substantially underneath the first stop, whereby flexing of the leaf will be held within the curved surface of the stops.

15. A sub-press comprising a punch holder and a die shoe maintained in facing spaced relationship, said spaced relationship being maintained by a plurality of substantially rigid arms extending from one side of the punch holder to predetermined points, a like number of arms extending from the same side of the die shoe adjacent to said predetermined points, and a like number of aligned flexible leaves joining the end of each punch holder arm to the complementary die shoe arm whereby movement of the punch holder toward the die shoe will establish in the flexible leaves a plurality of fulcrums lying substantially in a single axis.

16. For use in a conventional power press brake, a sub-press comprising a die holding means having a width approximating the breadth dimension for the work of the press brake in which the sub-press is to be used and a depth dimension substantially exceeding the depth dimension of the bed of the press brake so that said sub-press die holding means when positioned on the press brake bed will project forwardly and rearwardly thereof, a plurality of arms extending from one side of said sub-press die holding means to predetermined aligned points, punch holding means above the die holding means and of similar dimensions, a plurality of arms extending from one side of the punch holding means so that their ends are adjacent to said predetermined aligned points, whereby one arm attached to the punch holding means and the adjacent arm attached to the die holding means may be considered as a pair of complementary arms, and means joining the free ends of each pair of complementary arms for holding the same in said assembled relationship and for permitting movement of the punch holding means toward the die holding means, said plurality of means being in substantial alignment so that the punch holding means and die holding means may be moved toward and away from each other along an arc.

17. A sub-press comprising means for holding punches, means for holding dies, a plurality of substantially rigid arms extending from one side of the punch holding means to predetermined points lying in transverse alignment, a like plurality of arms extending from the die holding means to points adjacent to such predetermined points whereby one arm attached to the punch holding means and the adjacent arm attached to the die holding means may be considered as a pair of complementary arms, and a like number of joining means connecting the free ends of each pair of complementary arms at said predetermined points and for permitting movement of the punch holding means toward and away from the die holding means in an arc about said joining means.

18. A sub-press comprising a punch holder and a die shoe maintained in facing spaced relationship, said spaced relationship being maintained by a plurality of substantially rigid arms extending from one side of the punch holder to prede-

termined points, a like number of arms extending from the same side of the die shoe adjacent to said predetermined points, a like number of aligned flexible leaves joining the end of each punch holder arm to the complementary die shoe arm whereby movement of the punch holder toward the die shoe will establish in the flexible leaves a plurality of flexing points lying substantially in a single axis, and means for positively limiting the degree of bending of each of said aligned flexible leaves.

19. A sub-press comprising a pair of tool hold-

ing members disposed in facing relationship and means for joining said tool holding members to each other along adjacent sides so that their opposite free sides, adapted to hold tools, may move toward and away from each other along a limited arc, said tool holding members having substantially equal ability to resist distortion whereby forces set up by a punch entering a work piece will distort both tool holding members equally and thereby maintain substantial alignment thereof.

FREELAND H. LESLIE.
